(57) **CLAIM**

The ornamental design for a control device for public safety vehicle, as shown and described.

DESCRIPTION

FIG. 1 is a perspective view of an ornamental design for a control device for public safety vehicle;

FIG. 2 is a front view thereof;

FIG. 3 is a rear view thereof;

FIG. 4 is a first side view thereof;

FIG. 5 is a second side view thereof;

FIG. 6 is a bottom view thereof; and,

FIG. 7 is a top view thereof.

The broken line in FIGS. 1-7 showing environmental structures is for illustrative purposes and forms no part of the claim design.
